UNITED STATES PATENT OFFICE.

NATHAN DURBIN, OF TAYLORVILLE, ILLINOIS.

SPLICE-BAR.

1,132,312.

Specification of Letters Patent. Patented Mar. 16, 1915.

Application filed July 10, 1914. Serial No. 850,191.

To all whom it may concern:

Be it known that I, NATHAN DURBIN, a citizen of the United States, residing at Taylorville, in the county of Christian and State of Illinois, have invented new and useful Improvements in Splice-Bars, of which the following is a specification.

The present invention relates to means for connecting the ends of two rails for sustaining the same in alinement, and is in the nature of an improvement over the rail joint for which I was granted on May 12, 1914 United States Patent No. 1,096,696.

Another object of the invention is the construction and arrangement of parts whereby two rail ends may be effectively connected and sustained against lateral or vertical movement, but wherein the joint will not interfere with the longitudinal movement of the rails incident to the expansion and contraction thereof.

Other objects and advantages will appear as the nature of the improvement is more fully understood, reference being had to the accompanying drawings wherein there is illustrated a simple and satisfactory reduction of the invention to practice.

In the drawings: Figure 1 is a perspective view of two rails connected in accordance with the present invention, Fig. 2 is a top plan view, Fig. 3 is a transverse sectional view approximately on the line 3—3 of Fig. 2, Fig. 4 is a similar view approximately on the line 4—4 of Fig. 2, Fig. 5 is a detail perspective view of the supporting member, Fig. 6 is a similar view of the chair member, and Fig. 7 is a detail perspective view of the rail ends, looking toward the side thereof provided with the notches.

In the drawing, in which like characters of reference designate corresponding parts throughout, 1—1 designates two rails which have their ends abutting. The rails are of the ordinary construction, and the base flanges of the same have the edges cut away at an inward angle whereby, when the said rail ends abut, a V-shaped recess 2 is formed at the ends of said rails.

The numeral 3 designates a rail chair, 50 which includes a horizontally straight longitudinally extending base 4 that has formed on one of its longitudinal edges a vertical projection 5, the same having an integrally

formed angular flange 6 which extends inwardly over the base, and which has its end 55 formed with a vertical extension 7. The base 4 projects or extends a suitable distance beyond the vertical member 5, the said extending portion having notches arranged therein at suitable intervals to receive the 60 shanks of spikes 8, the said spikes being driven into the supporting ties 9. Formed adjacent the opposite longitudinal edge of the base 4 is a vertically arranged side or plate 10, the same having its upper edge 65 rounded inwardly to provide a lip 11, the lower face or wall of the said lip being arranged at an angle for a purpose which will presently be described. The inner face of the side or plate 10 at one end of the chair, 70 has a plurality of vertically arranged depressions 12 which communicate with openings 13 in the lip 11, and which also communicate with pockets 14 in the base 4 of the chair 3. The base projects a suitable 75 distance beyond the outer wall of the side or plate 10, the said projection being provided with a plurality of notches, each adapted to receive spikes 8 which enter the ties 9.

The numeral 17 designates the member which I term the support for the joint. This member includes a base plate 18 which is adapted to rest upon the base 4 of the chair 3 and to have its longitudinal edges contact 85 with the vertical members 5 and 10 formed with the base 4. The longitudinal edge of the base 18, contacting with the side 10 of the chair, is formed with a vertical extension 19 of a height corresponding to the distance between the upper face of the base 4 and the underface of the lip 11, so that the said portion 19 will contact with both the inner faces of the member 10 and the lower angular face of the member 11, while integrally 95 formed with the vertical extension 19 is an angular flange 20 which extends inwardly of the base 18, overlying the same, and formed with the end of said flange 20 is a vertical plate 21. The rails 1—1 are adapted to have 100 their base flanges rest upon the base 18 of the support 17, while one of the longitudinal edges of the base flanges of the said rails is contacted by the inner wall of the vertical extension 19 of the support, the upper angular face of said base being engaged by the 105

flange 20, while the plate 21 contacts with the webs of said rails, the upper edge of said plate contacting with the underfaces of the heads of the rails. The opposite longitudinal edge of the base of the rail is contacted by the plate 5, the upper faces of the same being engaged by the flange 6, while the vertical extension 7 of the chair contacts with the lower portions of the webs 10 of the rails, as will readily be noted from the drawings.

The vertical extension 19 of the support 17, at one of the ends of the said support is provided with a plurality of vertically disposed depressions 22, one of which registers with one of the depressions 12 in the side or plate 10, so that the shank 23 of a headed pin or key 24 may be inserted through one of the openings 13 and passed through the 20 registering depressions so that the lower portion of said key will be seated within one of the pockets 14 of the base 4 of the chair. As the head of the pin or key is arranged at a right angle to the shank thereof and as 25 the upper portion of the side 10 is rounded, it will be noted that a space is provided between the said head and the upper portion of the side to permit of the insertion of a pinch bar so that the pin or key may be 30 readily withdrawn to release the support from the chair when desired.

The vertical side 10 of the chair which has its end provided with depressions 12 is arranged at a less distance away from the 35 vertical member 5 of the said chair than is the said member 10 at the opposite end of the chair, and so it will be noted that the said member 10 is inclined from one of the ends of the chair to the opposite end, and 40 likewise the member 19 of the support, which is provided with grooves 22, is arranged at a less distance away from the opposite longitudinal edge of the base of the support than is the second or opposite end 45 of the support. In other words, the portion 19 has its outer face gradually increasing in width and thickness from one of its ends to its opposite end and so the removal of the key to permit of the proper adjustment of 50 the support with relation to the chair is highly desirable.

The flange 6 adjacent the vertical member 5 is provided with an opening 25 which is arranged centrally of the chair, and which 55 registers with an elongated notch 26 provided in the end of the base 18 which abuts with the wall 5 of the chair, while the base 4 of the chair is provided with an opening 27 which registers with the opening 25, and 60 passing through the registering openings and through the elongated notch 26 is a pin or bolt 28 which is disposed within the V-shaped recess 2 in the ends of the rails and which serves as a means for preventing the

creeping of the rails, after the same is arranged within the path of contact with the ends of both of the rails.

The vertical extension 7 of the flange 6 has its inner face provided with a longitudinally extending channel 30 which materially adds to the flexibility of the said plate 7, so that the same will tightly contact with the webs of the rails and the said passage or channel may also provide for the reception of a bonding member between the 75 rails.

From the above description, taken in connection with the accompanying drawings, the simplicity of the device, as well as the advantages thereof will, it is thought, be 80 perfectly apparent to those skilled in the art to which such invention appertains without further detailed description.

Having thus described the invention, what I claim is:

1. In a rail joint, two abutting rails each having its base flange at one of its edges notched at its end, an angular supporting plate upon which the rails rest, a joint chair for the plate, and a pin passing through the 90 support and through the base of the chair disposed between the notches at the rail ends.

2. In a rail joint, a support upon which the meeting ends of two rails rest, said support including a vertical member which engages with one of the longitudinal edges of the rails, an angular plate overlying the base flanges of the rails and a vertical extension contacting with the webs and underlying the heads of the rails, the said vertical member having its outer edge inclined from one end to the other, and provided with vertical depressions at its narrower end, a chair including a base upon which the base of the support rests and having a vertical member adjacent one of its longitudinal edges provided with an angular flange and a vertically extending plate, said members adapted to engage with the sides of the rails opposite that contacted by the members of the support, the base of said chair being provided adjacent its other longitudinal edge with a vertical side having a rounded upper portion which terminates in a lip having an inclined wall which contacts with 115 the inturned flange of the support, the inner wall of the said side plate being inclined from one end to the other end thereof, the inner face of said side having a plurality of spaced depressions, the base having pockets 120 registering with the depressions and the rounded head of said side having a plurality of spaced openings also registering with the depressions, the supporting member adapted to be moved longitudinally of the base to bring one of its depressions into register with one of the depressions in the said side, a key including a shank and an an-

gular head adapted to be inserted through the
opening in the side into the registering de-
pressions and to rest within the pocket in
the base, and means provided between the
5 chair and support disposed within a notch at
the ends of the rails for preventing the
creeping of the rails.

In testimony whereof I affix my signature
in presence of two witnesses.

NATHAN DURBIN.
